MODULAR HOUSE

Emil A. Tessin II, Cuyahoga Falls, Ohio, assignor to Alside Homes Corporation, a corporation of Ohio

Filed Oct. 22, 1962, Ser. No. 72,208

Term of patent 14 years

(Cl. D13—1)

FIG. 1

I claim:

The ornamental design for a modular house, as shown and described.
